(57) **CLAIM**

The ornamental design for a protective face mask for water sports, as shown and described.

DESCRIPTION

1. Protective face mask for water sports

1.1 : Right perspective

1.2 : Front perspective

1.3 : Left perspective

1.4 : Left perspective

1.5 : Back

1.6 : Unfastened and partly folded left side

The design shows a new, original and ornamental design for a protective face mask for water sports as shown in the drawings; Fig. 1.1 to Fig. 1.5 show the protective face mask in a configuration in use; Fig. 1.6 shows the face mask in a folded manner.
